GAS TANK LOCK

Samuel Greenberg, Chicago, Ill.

Application March 8, 1941, Serial No. 382,313

5 Claims. (Cl. 220—86)

This invention relates to certain novel improvements in gasoline tank closures and constitutes an improvement over that shown in Patent No. 2,224,385, granted to me on December 10, 1940, on a self-locking tank cap.

The present invention has for one of its principal objects the provision of an improved construction which will be highly efficient in use and economical in manufacture.

More specifically the invention has for its salient object the provision of an improved closure for gasoline tanks of automobiles wherein the closure cannot be removed and wherein the cap is securely locked in closed position to prevent the theft of gasoline from the tank.

A still further object of this invention is the provision of a gasoline tank closure which may be associated with the conventional neck of the gasoline tank without modifying the latter and without the employment of tools or the like. In other words, the closure may be applied to the neck by a person of ordinary skill.

Other objects will appear hereinafter.

The invention consists in the novel combination and arrangement of parts to be hereinafter described and claimed:

Fig. 1 is a bottom view of the closure embodying my invention with a portion thereof broken away;

Fig. 2 is a sectional detail view of the same showing the closure associated with the neck of a gasoline tank;

Fig. 3 is a perspective view of the preferred lock embodied in my invention;

Fig. 4 is a part sectional perspective view of the invention, illustrating its relationship with the neck of a gasoline tank during the adaptation of the same to the neck;

Fig. 5 is an enlarged sectional detail view showing the latching means embodied in my invention; and

Fig. 6 is a sectional detail view of the same taken substantially on line 6—6 of Fig. 5.

The drawing herein described and illustrated shows the preferred form of construction of my invention. To understand the advantages of the present invention, I will first describe the conventional neck of a gasoline tank as shown in Figs. 2 and 4. In this connection the neck is indicated at 10 and embodies the usual inturned latching lip 11 having a depending lug 12 adjacent the entrance path 13. This neck 10 is formed as an integral part of the tank, and it is through this neck that gasoline is fed into the tank.

My improved closure comprises a closure ring 14, the marginal outer portion of which is turned down to provide a depending flange 15. The inner marginal portion of the ring 14 is likewise turned down to provide a flange 16. Between these flanges 15 and 16 there is arranged a packing or sealing washer 17. The flange 16 at opposite diametrical positions provides depending lugs 18. Each of these lugs 18 provides laterally parallel extending spaced ears 19. To the lug 18 between these ears 19 is pivoted as at 20 a latching dog 21. This dog 21 is provided with an offset portion 22, the edge 23 of which is substantially concave as at 24 for reasons presently to be explained. The dog 21 is normally urged into latching position by a spring means coiled about the pivot pin 20 with one end 25 engaging one of the ears 19 and the other end 26 bearing upon the dog 21 as shown in Fig. 4.

Hinged to this closure ring 14 as at 27 is a self-opening cap 28 of any desired formation, but preferably including an annular depending flange 29 extending a substantial distance below the flange 15 so as to discourage and minimize the possibility of insertion of a tool to wedge the cap from locked position.

Centrally located within the cap 28 is a cylinder 30 and within this cylinder 30 is arranged a key barrel 31. This key barrel is part of a lock structure comprising oppositely disposed spring-controlled lock bolts 32, each bolt having its outer end turned upwardly as at 33 and provided with tumbler slots 34 for engagement with the tumbler 35 which urges the bolts 32 from locked to unlocked position against the action of the springs 36.

Formed in the flange 16 at opposite diametrical points are slots 37 which permit the passage of these upturned portions 33 of the bolts 32 into latched engagement with the adjacent edges 38 of the flange 16 when the cap is disposed in locked position.

In applying the closure to the neck 10, the depending lugs 18 are inserted through the entrance paths 13 into the neck, with the sealing washer 17 resting upon the inturned edge of the neck. In this position the operator grasps the closure in his hand and firmly and steadily rotates the closure in a horizontal plane in a clockwise direction with respect to the neck 10. This will bring the concave portions 24 of the locking dogs 21 into engagement with the latching lip 11 and urge the locking dogs clockwise as seen in Fig. 5 against the action of the spring means. Continued rotation of the closure in clockwise direc-

tion rotates the lock dogs 21 in a vertical plane and cams the lock dogs 21 against the tapered edge 11' of the lip 11 and in proportion of the distance the lock dogs move relative to the edge 11' the distance from the edge 11' to the pivot pin 20 of the dog 21 is decreased thus tensioning the coil spring. This rotation is continued until the locking dogs 21 are disposed in the position shown in Fig. 5. The locking dogs 21 when disposed in the position shown, place the springs of these dogs under compression and these springs in that condition will serve to constantly urge the locking dogs toward the edges 11' and although an effort to rotate the cover opposite to clockwise direction would normally release the pressure of the lock dog 21 against the cam edge 11' the coil spring is so tensioned as to keep the concaved portion 24 firmly against the edge 11' without slipping relative thereto thus binding the cover relative to the neck portion 10. In this regard it will be noted in Fig. 5 that by reason of the pressure of the spring means, the lock dog 21 is constantly urged counterclockwise and that the portion 24 is set into firm engagement with the edge 11' in such a manner that when an attempt is made to rotate the cover 14 counterclockwise the swing of the dog 21 relative to its pivot 20 is greater in proportion to the increase in distance from the pivot 20 to the edge 11', the dog 21 thus forming a strut member which binds the cover against counterclockwise rotation.

To complete the invention I provide between the closure ring 14 and the cap 28 a sealing washer 40. This sealing washer 40 is carried by the cap and encircles the cylinder 30.

From the description herein it is manifest that I provide a closure which is firmly held in position upon the neck by a means which is of simple structure and economical in manufacture. It is also apparent that I provide a closure ring adapted for permanent attachment to the neck of a receptacle or tank with a self-locking closure cap, which cap is also self-opening when unlocked.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having thus described my invention, what I claim as new and desire to protect by Letters Patent is:

1. In a closure member for receptacles having a tubular neck including an inwardly extending rim with a downwardly disposed flange, said flange having notched out portions and a shoulder extension formed adjacent thereto with the lower edge of said flange increasing in depth from the notched portion to the opposite shoulder, in combination a closure ring including oppositely disposed depending lugs, a locking member pivotally arranged on said lugs, pivot means mounting the locking member on said lug, said locking member having its free end portion disposed to be engaged by the lower edge of said flange when the closure ring is rotated in one direction on said neck, and spring means between said depending lug and said locking member.

and urging said locking member into engagement with said lower edge of said flange to prevent rotative movement of the closure ring in a direction opposite to said first named direction.

5. 2. In a closure member for receptacles having a tubular neck including an inwardly extending rim with a downwardly disposed flange, said flange having notched out portions and a shoulder extension formed adjacent thereto with the lower edge of said flange increasing in depth from the notched portion to the opposite shoulder, in combination a closure ring including oppositely disposed depending lugs, a locking member pivotally arranged on each of said lugs, 10 pivot means mounting the locking member on said lug, said locking member having its free end portion disposed to be engaged by the lower edge of said flange when the closure ring is rotated in one direction on said neck, and spring 15 means on said pivot means and having one end anchored on said depending lug and its opposite end in engagement with said locking member urging said locking member into engagement with said lower edge of said flange to prevent 20 rotative movement of the closure ring in a direction opposite to said first named direction.

3. In a closure member for receptacles having a tubular neck including an inwardly extending rim with a downwardly disposed flange, said flange having notched out portions and a shoulder extension formed adjacent thereto with the lower edge of said flange increasing in depth from the notched portion to the opposite shoulder, in combination a closure ring including 25 oppositely disposed depending lugs, a locking member pivotally arranged on the exterior face of each of said lugs, pivot means mounting the locking members on said lugs, stop means on the exterior face of said lugs and adapted to limit 30 rotative movement of said locking member, said locking member having its free end portion disposed to be engaged by the lower edge of said flange when the closure ring is rotated in one direction of said neck, and spring means arranged 35 on said pivot means between the locking member and one of said stop means and adapted to urge said locking member into engagement with said lower edge of said flange to prevent 40 rotative movement of the closure ring in a direction opposite to said first named direction.

4. In a closure member for receptacles having a tubular neck including an inwardly extending rim with a downwardly disposed flange, said flange having notched out portions and a shoulder extension formed adjacent thereto with the lower edge of said flange increasing in depth from the notched portion to the opposite shoulder, in combination a closure ring including 45 oppositely disposed depending lugs, a locking member pivotally arranged on the exterior face of each of said lugs, pivot means mounting the locking members on said lugs, stop means on the exterior face of said lugs, and adapted to limit 50 rotative movement of said locking member, said locking member having its free end portion disposed to be engaged by the lower edge of said flange when the closure ring is rotated in one direction of said neck, and spring means arranged 55 on said pivot means between the locking member and one of said stop means and adapted to urge said locking member into engagement with said lower edge of said flange with said 60 locking member disposed for binding action relative to said flange to prevent rotative movement.

of the closure ring in a direction opposite to said first named direction.

5. In combination with the neck of a gasoline tank having a locking rim, including an internal flange with opposite notches and stopping shoulders adjoining each notch, said flange having a cam edge depending therefrom and increasing in depth from one end near one of said notches to an opposite end near one of said shoulders, a closure ring for said neck and including oppositely disposed parallelly extending supporting lugs extending below said rim when said closure ring is disposed on said neck, locking dogs and pivot means carried by said lugs to dispose said locking dogs for rotative movement 15

in the direction of said cam edge, spring means arranged between said supporting lugs and said locking dogs to urge the latter into cammed arrangement with said cam edge whereby to permit rotation of said closure ring in one direction relative to said neck, said locking dogs forming strut means between said cam edge and said pivot means and adapted to bindingly swing toward said cam edge a distance greater in proportion with respect to the increase in distance from the pivot means to said flange when said closure ring is rotated in an opposite direction relative to said neck.

SAMUEL GREENBERG.
